Primary Examiner — W. A. Teddy Falloway

(74) Attorney, Agent, or Firm — Patricia C. Brzostowicz;
Superior Patent Group, LLC(57) **CLAIM**

The ornamental design for a food service box as shown and described.

DESCRIPTION

FIG. 1 is a perspective view showing a food service box of Applicant's new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines in the drawings illustrate portions of the food service box and/or environment, which form no part of the claimed design.

1 Claim, 7 Drawing Sheets(56)
